UNITED STATES PATENT OFFICE.

JULIUS H. BECKER, OF SAN FRANCISCO, CALIFORNIA.

FRICITION HEAT-GENERATOR.

1,126,354.

Specification of Letters Patent. Patented Jan. 26, 1915.

Application filed February 2, 1914. Serial No. 816,013.

To all whom it may concern:

Be it known that I, JULIUS H. BECKER, a citizen of the United States, residing in the city and county of San Francisco and State of California, have invented new and useful Improvements in Friction Heat-Generators, of which the following is a specification.

This invention relates to a centrifugally actuated friction heat generator.

The object of the present invention is to provide a simple, substantial, easily operated water heater or steam generator for heating systems, in which smoke stacks and boilers, with connected mechanism, may be entirely eliminated.

The invention includes a water heater or steam generator in which a centrifugally actuated friction device is employed to generate the heat.

The invention further consists of certain details of construction, combinations and arrangements of parts, all of which will be hereinafter more particularly set forth and claimed in the accompanying drawings and specifications.

Figure 1 is a longitudinal vertical section through the generator. Fig. 2 is a transverse section.

Referring to the drawings, A indicates a horizontally positioned cylinder, supported by lugs 2 on a suitable bearing frame 3, and 4 is a water jacket formed integral with the cylinder and entirely surrounding same. Suitably journaled in bearing members 5, formed on a pair of end plates or heads 6 and 7, secured to the cylinder, as at 8, is a shaft 9 which extends through the cylinder in a concentric position with relation to the inner surface of same.

Keyed upon the shaft, as at 10 and 11, within the cylinder, between the end plates 6 and 7, is a pair of hexagonal shaped collars 12 and 13, and supported between said collars is a suitable number of bearing rods 14. Resting upon the several faces of the collars 12 and 13 and extending a sufficient distance beyond same, to practically reach from end to end of the interior of the cylinder A, is a corresponding number of plates 15, each of which is provided with a downwardly turned, hook-shaped lug 16 adapted to engage with the rods 14, and secured on the outer face of each plate by bolts 17 is a friction shoe 18.

The shaft 9, with connected collars 12 and

13, plates 15 and shoes 18 are revolved as a unit within the cylinder and the shaft may be directly connected to an electric motor, or any other suitable driving mechanism, not here shown. The centrifugal motion thus transmitted forces each shoe 18 out into frictional engagement with the interior face of the cylinder, and the heat thus generated is radiated through the cylinder wall to heat the water contained in the jacket or for the purpose of generating steam.

The pivotal mounting of each friction shoe, which is produced by the connection formed between the rods 14 and the hook-shaped lugs 16, allows each shoe to contact and seat itself upon the interior surface of the cylinder. A perfect contact between the friction shoe and cylinder is thus made and the highest friction efficiency produced. Any wear or variation in the hardness of the material of the friction shoe is thus automatically taken up and adjusted one independent of the other. The outside surface and ends of the cylinder may be covered with a suitable form of heat-insulating material and practically all losses, by radiation, in this manner may thus be prevented.

The capacity of the generator constructed as here shown may be greatly increased or decreased to suit various conditions by simply increasing or decreasing the number of friction shoes carried upon the collars 12 and 13. The friction surface is thus reduced or increased with a consequent change in heating or generating capacity within the jacket 4, and a standard size of unit may thus be employed, the capacity of which may be greatly varied to suit various conditions.

The generator operated in the manner here shown eliminates all dangers of fire, and the cost of installation is very small, compared with the standard heating plants now employed, as burners, smoke-stacks and boilers, with the connected parts, are entirely eliminated.

The materials and finish of the several parts of the generator are such as the experience and judgment of the manufacturer may dictate.

Having thus described my invention, what I claim and desire to secure by Letters Patent is—

1. A friction heater and steam generator comprising in combination, a water-jacketed cylinder, a driving shaft extending through

the cylinder, a rotor within the cylinder secured to the shaft, and a plurality of friction members engageable with the interior surface of the cylinder mounted in the rotor.

5. 2. A friction heater and steam generator comprising in combination, a water-jacketed cylinder, a driving shaft extending through the cylinder, a rotor within the cylinder secured to the shaft, and a plurality of friction shoes engageable with the interior surface of the cylinder pivotally mounted on the rotor.

10. 3. A friction heater and steam generator comprising in combination, a water-jacketed cylinder, a driving shaft extending through the cylinder, a pair of disks secured to the shaft spaced with relation to each other and the ends of the cylinder, a plurality of rods carried by the disks, and a plurality of friction shoes engageable with the interior surface of the cylinder pivotally mounted on said rods.

15. 4. A friction heater and steam generator comprising in combination, a water-jacketed cylinder, a driving shaft extending through the cylinder, a pair of disks secured to the

shaft spaced with relation to each other and the ends of the cylinder, a plurality of rods carried by the disks, a plate pivotally secured on one edge to each rod, and a friction shoe secured on each plate adapted to be thrown into engagement with the interior surface of the cylinder by centrifugal action.

20. 5. A friction heater and steam generator comprising in combination, a water-jacketed cylinder, a driving shaft extending through the cylinder, a pair of disks secured to the shaft spaced with relation to each other and the ends of the cylinder, a plurality of rods carried by the disks, a plate pivotally secured on one edge to each rod and radially adjustable upon same, and a friction shoe secured on each plate adapted to be thrown into engagement with the interior surface of the cylinder by centrifugal action.

25. In testimony whereof I have hereunto set my hand in the presence of two subscribing witnesses.

JULIUS H. BECKER.
